(57) **CLAIM**

The ornamental design for a shoe, as shown and described.

DESCRIPTION

FIG. 1 is a rear, right, top perspective view of a shoe showing our new design;

FIG. 2 is a rear, left, top perspective view thereof;

FIG. 3 is a right side view thereof;

FIG. 4 is a left side view thereof;

FIG. 5 is a top view thereof;

FIG. 6 is a bottom view thereof;

FIG. 7 is a rear view thereof;

FIG. 8 is a front view thereof; and,

FIG. 9 is a cross-sectional view taken along line 9-9 in FIG. 3.

In the drawings, the broken lines show portions of the shoe that form no part of the claimed design. The oblique line shading in the drawings indicates translucent surfaces.
